POWER HANDLE FOR A TOOTHBRUSH

Beverly Bond, South Norwalk, Conn., and David E. Eberhart, Bound Brook, N.J., assignors to Ronson Corporation, Woodbridge, N.J., a corporation of New Jersey

Filed Jan. 7, 1964, Ser. No. 78,099

Term of patent 14 years

(Cl. D9—2)

FIG. 1 is a side elevational view of a power handle for a toothbrush showing our new design;

FIG. 2 is a bottom view thereof;

FIG. 3 is a top view thereof;

FIG. 4 is a front view thereof; and

FIG. 5 is a rear view thereof.

The broken line showings of the toothbrush, electric plug and cord, are for illustrative purposes only, the cord being shown broken away for convenience of illustration.

We claim:

The ornamental design for a power handle for a toothbrush, substantially as shown and described.
